UNITED STATES PATENT OFFICE.

ALEXANDER WEMYSS, OF PHILADELPHIA, PENNSYLVANIA, ASSIGNOR TO
CHARLES NOBLE, M. D., CHARLES NOBLE, AND FRANCIS P. NICHOLSON,
OF SAME PLACE.

DESIGN FOR STOVE-DOOR.

Specification forming part of Design No. **7,160**, dated February 10, 1874; application filed January 10, 1874.
[Term of Patent 3½ years.]

To all whom it may concern:

Be it known that I, ALEXANDER WEMYSS, of Philadelphia, Pennsylvania, have invented a Design for a Stove-Door and Frame, of which the following is a specification:

The figure in the accompanying drawing fully illustrates my design for the door of an upright heating-stove.

The door-frame A is curved throughout, to conform to the shape of the stove-casing, and has the peculiar outline shown, the sides *a a* being straight and parallel, and the upper and lower edges, *b* and *d*, being composed of a succession of short curved and straight lines, joining each other at angles more or less abrupt. The hinged door B projects outward from the frame, and has three panels, *h*, *h'*, and *h''*, the partitions between which and the beadings *i* and *j* above and below the same are ornamented by diamond-shaped and foliated figures, as shown. There are beaded and foliated ornaments on the heading *k*, which accords with and projects outward to meet the panels, in the manner clearly represented in

the drawing, and below the door there is an ornamented base-plate, *m*, the lower outline of which is similar to that of the door-frame. On the door, at the top of each panel, there is a small rosette, *n*, and the door-frame is ornamented, near its edges, by a number of similar rosettes, *n'*.

I claim—

1. The design for a door-frame, curved at the upper and lower edges, and ornamented by rosettes *n*, as shown.
2. The design for a door, having open panels and triangular head and base, and embellished by the diamond-shaped and foliated figures at the edges of the panels, the parallel moldings *i* and *j*, and the beaded and foliated ornaments *k* and *m*, as set forth.

In testimony whereof I have signed my name to this specification in the presence of two subscribing witnesses.

ALEXANDER WEMYSS.
